UNITED STATES PATENT OFFICE

CHARLES HAROLD CLARKSON, OF TORONTO, ONTARIO, CANADA

HEAD COPE

Application filed November 3, 1930. Serial No. 493,007.

This invention relates to devices such as may be interposed between a hat and the wearer's head to adapt the shape of the one to the shape of the other. Heretofore, as the shape of the hat is fixed, save as it may be more or less flexible, adapters have been fitted to the hat and adjusting means have been provided in an attempt to make the combination fit the wearer's head but no means have so far been provided which will enable a fit to be attained with certainty.

In the present invention I have adopted the plan of first fitting a shape-retaining cope or adapter to the head and then securing to the cope a hat of suitable size and shape. By following this course I am enabled to eliminate all guess-work in fitting and to make a cope that accurately fits as much of the head as may be necessary, providing a bearing on the head many times larger than any heretofore produced, thus reducing pressure on and therefore wear (or atrophy) of blood-vessels of the scalp and relieving pressure in any areas specially subject to injury or trauma. A common cause of baldness is thus removed. These relief areas may be produced by first placing over the head a form covering all prominences, ridges, arterial areas or abnormalities. Then a stamped (prepared) cope form is superimposed and pressed and manipulated so that its surface is adjusted accurately to this head with the danger areas protected by the said relief form. We then have a cope which avoids pressure over any points of wear or trauma and yet is supported by the greatest possible area of scalp.

The invention is hereinafter more fully described and is illustrated in the accompanying drawings in which

Fig. 1 is a side elevation, partly in section, of a cope constructed in accordance with my invention and positioned in a hat;

Fig. 2 a cross section of part of a cope;

Fig. 3 a plan view;

Fig. 4 a plan view of a modified form; and

Fig. 5 a side elevation of the same.

In the drawings like numerals of reference indicate corresponding parts in the different figures.

1 is a piece of material sufficiently pliable to be pressed to shape and sufficiently stiff to tend to maintain its form after shaping. Suitable material for this purpose is wire gauze of from twelve to twenty mesh. A piece of this material is shaped on a suitable form to approximately the shape of the upper part of the wearer's head. I thus obtain a concavo-convex structure with a margin substantially inextensible at four diametrically opposite parts of its margin, between which the margin is more or less stretchable owing to the biasing, or diagonal crossing, of the wire strands at such intermediate points. In practice a number of standard shapes may be kept in stock requiring but little further shaping to fit the individual head. The concavo-convex structure thus formed is fitted to the wearer's head in such a manner that its inner surface engages a considerable area of the wearer's scalp, while the margin may be more or less raised therefrom at the back and front, the intent being to avoid pressure on the scalp along lines of wear or traumatism and to engage as large surfaces as possible at less vulnerable localities.

The holding in shape of the margins of the structure is largely effected by folding the margin to form the band 2. Usually a double fold will be employed.

As the height of the dome of the head varies in different individuals, I find it necessary to provide means for readily varying the height of the dome of the cope and for this purpose I form in the cope the bead or roll 3 extending round the device intermediate of the top and the margin. When the cope is fitted to the head, this bead may be

more or less flattened out, or pinched up as the case may be, to allow the margin of the cope to be brought down to the desired position on the head in line with the inner edge 5 of the hat brim.

To assist in retaining the structure in shape and place as fitted, I prefer to employ one or more tensioning bands 5 extending from one side of the rim of the device to the 10 other above the said rim. These are connected to or integral with plates 7 secured to the margin of the cope at opposite sides. These bands 5 are so curved as to press the plates 7 and therefore the sides of the cope against 15 the wearer's head, thus relieving the pressure of the cope in the neighborhood of the supra- 20 arital and occipital arteries. After the cope has been molded to the head, the cope may be set in shape by a stiffening coat such as pyroxylin cement. Such stiffening, or any equivalent is particularly desirable where the wires are in bias at the margin or in the 25 band of the cope.

When the structure is completed it may 25 be secured to the inside of a hat, from which, if necessary, the sweat band may be removed. The connection may be in any desired manner as, for example, by sewing or by the use 30 of metal clips or dome fasteners or by the use of a pyroxylin cement.

The plates 7 have pins 8 secured thereto provided with sleeves 10 which pass through the sides of the hat 9. Washers or nuts 11 on the pins prevent the hat disengaging. 35 There is thus provided sufficient play for the band 2 of the cope without interference from the more or less stiff hat brim. As it may sometimes be necessary to relieve the inward pressure of the sides of the cope, I secure the 40 lazy-tongs levers 11 to the ends of the pins 8. These levers pass round the hat to the front and their ends 12 may be gripped by the fingers to spread their rearward ends and therefore the sides of the cope.

A spring 15 may be employed to cause the levers 11 to aid the bands 5 in imparting inward pressure to the sides of the cope, and stops 16 to limit their inward movement.

While the device may be used without any 50 hat band, pieces of felt or leather 13, or other suitable material, may be secured to the interior of the structure about the rim, as may be found necessary because of lack of hair to protect the scalp. Such pieces may be 55 partly held by the band 2 as shown.

To provide additional security against accidental displacement of the device when in use, more particularly where there is little or no parallelism of the sides of the wearer's 60 head, it is desirable to weigh the cope to lower its center of gravity and to give increased downward pressure. For this purpose I provide the weights 14 secured in any suitable manner to the cope, preferably as 65 near the margin as possible. For use when

flying or motoring it may be necessary to provide extra retention and for this purpose I provide a flexible cord or cable connected to the margin of the cope at one side and at the other wound on a known form of tensioning device such as 6 in the drawings. This cable is inconspicuous and may, whenever necessary, be drawn out and engaged under the occipital protuberance. 70

In Figs. 4 and 5 a modification of the device is shown in which the wire gauze is dispensed with. In this form a plate 7^a is provided at each side of the structure, these plates being connected by curved bands 5^a suitably connected with a curved fore-and-aft band 17 extending over the crown of the head from back to front. The arms being resilient are thus resiliently hinged on the structure and are suitably shaped to cause an inward pressure of the plates 7^a against the 85 sides of the wearer's head. In order that the plates may be spread to release their pressure finger grips 12^a are secured to the bands 5^a. These finger grips, when the device is used with a soft felt hat, are easily actuated 90 by pressure exerted through the sides of the top of the hat. The plates 7^a are preferably also connected over the top of the structure by means of a flexible band 18 secured to the band 17 and passing through loops 19 formed 95 integrally in the plates 7^a adapted to frictionally grip the band 18. The structure just described may be employed either with or without the concavo-convex wire structure and is capable of many modifications. 100

From the above description it will be seen that I have devised a head cope or hat adapter which will satisfactorily attain the object of my invention as set out in the preamble of this specification which was to distribute the weight and pressure of the device and hat on the scalp over considerable areas, to relieve the pressure where pressure is likely to do harm and to use compression only 110 on areas at opposite sides of the head more or less parallel and mainly free of important arteries and nerves or bony ridges, and to furnish a stable foundation for hats of any design or weight.

What I claim as my invention is:

1. A head cope comprising a form retaining concavo-convex structure of wire gauze fitted to the wearer's head and presenting surfaces of considerable area for engagement with the top of the head, and means associated with said structure tending to elastically press the sides of said structure against the sides of the head, thus relieving pressure at the back and front. 115

2. A head cope comprising a form retaining concavo-convex structure of wire gauze fitted to the wearer's head and presenting surfaces of considerable area for engagement with the top of the head and means associated with said structure, extending from 120 125 130

one margin to the other over the top of the structure tending to elastically press the sides of said structure against the sides of the head, thus relieving pressure at the back and front.

5. 3. A head cope comprising a structure fitted to the wearer's head and presenting surfaces of considerable area for engagement with the top of the head, the said structure being normally spaced from the wearer's head at the back and front, and means associated with said structure tending to elastically press the sides of said structure against the sides of the head, thus relieving pressure at the back and front.

10. 4. A head cope comprising a form retaining concavo-convex structure of wire gauze fitted to the wearer's head and presenting surfaces of considerable area for engagement with the top of the head, the said structure being normally spaced from the wearer's head at the back and front, and means associated with said structure, extending from one margin to the other over the top of the structure, and tending to elastically press the sides of said structure against the sides of the head, thus relieving pressure at the back and front.

15. 5. A head cope comprising a form retaining concavo-convex structure of wire gauze fitted to the wearer's head and presenting surfaces of considerable area for engagement with the top of the head, the said structure being formed with an annular stiffening band 20 formed of a marginal portion folded on itself.

25. 6. A head cope constructed in accordance with claim 1 having a plate secured at each side of the wire structure at its margin and a flat spring member connected at its ends 30 with said plates and extending over the crown of the device.

35. 7. A head cope constructed in accordance with claim 1 having a plate secured at each side of the wire structure at its margin and a flat spring member connected at its ends 40 with said plates and extending over the crown of the device, and members pivoted together at the front of the device and connected to said plates whereby the plates may be spread 45 to relieve the pressure of the device against the sides of the head when the device is to be removed from the head.

50. 8. A head cope comprising a form retaining concavo-convex structure of wire gauze fitted to the wearer's head and presenting surfaces of considerable area for engagement with the top of the head, said structure having a bead of surplus material pressed therein extending round the device intermediate 55 of the crown and the margin of the device.

60. 9. A head cope formed from a sheet of rectangular-meshed wire gauze pressed to concavo-convex form with its margin shaped as a closed curve, the device thus being relatively inextensible at four diametrically opposite

points between which the margin, owing to the biassing of the wire strands, is stretchable.

10. 10. A head cope formed from a sheet of wire gauze pressed to concavo-convex form 70 with its margin shaped as a closed curve, the device thus being relatively inextensible at diametrically opposite points between which the margin, owing to the biassing of the wire strands, is stretchable, the marginal portion 75 of the structure being folded on itself to form an annular band.

11. 11. A head cope comprising a form retaining concavo-convex structure of wire gauze fitted to the wearer's head in combination 80 with a hat secured to said cope at back and front, the margin of the cope being spaced from the head at the back and front and the hat spaced from said margin of the cope at the sides.

12. 12. A head cope comprising a form retaining concavo-convex structure of wire gauze fitted to the wearer's head in combination with a hat secured to said cope, the margin of the cope being spaced from the head at the 90 back and front and the hat spaced from said margin of the cope at the sides, and means associated with said cope tending to elastically press the sides of the cope against the sides of the head and away from the hat.

13. 13. A head cope comprising a form retaining concavo-convex structure of wire gauze fitted to the wearer's head and presenting surfaces of considerable area for engagement with the top of the head, means associated with said structure tending to elastically press the sides of said structure against the sides of the head, thus relieving pressure at the back and front, and weights secured to said cope positioned to lower its center of 100 gravity.

14. 14. A head cope comprising a form-retaining concavo-convex structure of wire gauze fitted to the wearer's head in combination with a hat secured to said cope having the 110 internal circumference of its brim greater than that of the margin of the cope, whereby the hat is supported in spaced relationship to the head.

15. 15. A head cope comprising a structure 115 adapted to rest on the wearer's head and including side plates; curved arms forming part of the structure adapted to exert an inward resilient pressure on said plates to press them against the sides of the wearer's head.

16. 16. A head cope comprising a structure adapted to rest on the wearer's head and including side plates; curved arms resiliently hinged on the structure and adapted to exert an inward pressure on said plates to press 123 them against the sides of the wearer's head; and finger grips connected to said arms forming means whereby the arms may be moved to release the plates.

17. 17. A head cope comprising a form retain-

ing concavo-convex structure fitted to the wearer's head and presenting surfaces for engagement with the top of the head, and means associated with said structure tending to elastically press the sides of said structure against the sides of the head, thus relieving pressure at the back and front.

Signed at Toronto, Canada, this 31st day of October, 1930.

CHARLES H. CLARKSON.
